Term of patent 7 years

(Cl. D54—13)

Fig. 3. Fig. 4. Fig. 5.

To all whom it may concern:

Be it known that I, Charles A. Carter, a citizen of the United States, and a resident of Altadena, California, have invented a new, original, and ornamental Design for Painter's Tool, of which the following is a specification, reference being had to the accompanying drawing which forms a part of said specification and in which drawing:

Fig. 1 is a side elevational view of a painter's tool showing my new design,

Fig. 2 is an edge elevational view,

Figs. 3 and 4 are, respectively, left and right hand end elevational views of the tool positioned as in Fig. 1,

Fig. 5 is a transverse sectional view taken on the line 5—5 of Fig. 1,

Fig. 6 is a medial, longitudinal, sectional view taken on the line 6—6 of Fig. 1, and

Fig. 7 is a transverse sectional view taken on the line 7—7 of Fig. 1.

I claim:

The ornamental design for a painter's tool, substantially as shown.
